UNITED STATES PATENT OFFICE.

SHERWIN GIBBONS AND HERMAN B. HENSEL, OF LANCASTER, CALIFORNIA.

WALL CONSTRUCTION AND METHOD OF FORMING THE SAME.

Application filed June 30, 1924. Serial No. 723,224.

To all whom it may concern:

Be it known that we, SHERWIN GIBBONS and HERMAN B. HENSEL, citizens of the United States, residing at Lancaster, in the 5 county of Los Angeles and State of California, have invented certain new and useful Improvements in a Wall Construction and Method of Forming the Same, of which the following is a specification.

10 This invention relates to new and useful improvements in wall structures and has for its principal object to provide a structure which may be easily and readily constructed and will further be water proof as well as 15 weather proof.

Another important object of the invention is to provide a wall structure of the character above described wherein reinforcing means is associated therewith, the same being 20 adapted to be embedded in the material used in the construction of the wall.

A further object is to provide a wall structure of the above mentioned character, which is simple in construction, inexpensive, strong 25 and durable and furthermore adapted for the purposes for which it is designated.

Other objects and advantages of this invention will become apparent during the course of the following description.

30 In the accompanying drawing forming a part of this specification and in which like numerals designate like parts throughout the same:

Figure 1 is a side elevation of our improved wall structure showing the various 35 steps in the construction thereof.

Figure 2 is a fragmentary vertical sectional view thereof.

Figure 3 is a transverse section showing 40 the spaced studs and the anchoring means associated therewith, and

Figure 4 is a detail perspective view of the woven wire engaging hook.

In the drawing wherein for the purpose 45 of illustration is shown the preferred embodiment of our invention, the numeral 1 designates a plurality of parallel spaced studs which are preferably formed of wood and the base of the wall structure is designated by the numeral 2. The studs 1 extend upwardly therefrom in the manner clearly illustrated in Figure 1. The studs or standards may be of any suitable thickness and arranged on the inner opposed sides 50 thereof are the anchoring members 3 which

are arranged in staggered relation as is more clearly illustrated in Figure 2. The purpose of the anchoring members will hereinafter be more fully described.

Extending outwardly from the opposite 60 faces of each standard or stud 1 are the fastening members 4, the same being provided to secure to the opposite faces of the spaced standards the woven wire 5. The woven wire which extends on the opposite 65 sides of the standards is also secured to the base 2 and at its upper end to a similar strip which extends across the ends of the standards (not shown).

For the purpose of preventing the outward bulging of the woven wire fabrics which extend across the opposite faces of the spaced studs or standards, the double ended hooks 6 are provided. The manner 70 in which the double ended hooks 6 cooperate with the opposed woven wire fabric 5 is clearly illustrated in Figure 2 of the drawing. Any number of these hooks may be used as is desired for accomplishing the purposes for which the same are designated. 75

To further prevent the downward sagging of the woven wire fabric during the filling of the spaces between the standards and the woven fabrics with dirt which has 80 been dampened, the temporary facing strips 7 are temporarily secured across the opposed faces of the spaced standards and spikes or the like such as are illustrated at 8 rest on the upper edges of the transversely extending temporary strips 7 and extend 85 through certain of the loops in the woven fabrics 5 on each of the opposed faces of the strips in the manners also clearly illustrated in Figure 2. With the woven wire

fabrics secured in position on the opposite 90 faces of the spaced strips and the supporting hooks arranged in position with respect to the woven wire fabrics, damped soil is deposited between the spaced strips and the woven wire fabrics on the opposite faces 95 thereof to entirely fill the spaces above formed for the entire length of the strips or standards. After the soil has been left standing for a suitable length of time, the temporary facing strips are removed and the spikes 8 will remain embedded in the 100 soil as will also the connecting hooks 6.

A coating B consisting of soil hydrated lime and cement which is mixed to form a substantially pasty substance is then plas- 110

tered over the whole surface covering the opposed faces of the strips and the wire fabric. The coating extends over the fastening elements 4 which extend outwardly from the opposed faces of the strip whereby the coating will adhere to the wooden studs or standards.

After the coating B has dried, a wash consisting of hydrated lime, cement, sand and water is applied with a brush or the like to the coating and any suitable coloring matter may be included in the wash as is desired.

The provision of a wall structure of the above mentioned character, will render the wall water proof as well as weather proof and will be inexpensive in its construction yet strong and durable. A similar structure may be used in the formation of floors or any other part of a building as may be desired and to prevent the cement from cracking at the ends of the studs or standards, metallic plates may be secured thereto.

While we have shown the preferred embodiment of our invention, it is to be understood that various changes in the size, shape and arrangement of parts may be resorted

to without departing from the spirit of the invention and the scope of the appended claim.

Having thus described the invention, what we claim is:—

The method of constructing a wall of the class described comprising in erecting parallel spaced studs, securing wire fabric to the opposed faces of said studs, placing temporary strips transversely across the opposed faces of the studs, connecting the woven wire fabrics together by double ended hooks to prevent the outward bulging thereof, inserting transversely extending pins through the woven wire fabric and resting the same on the upper edges of the transversely extending temporary strips, filling the spaces formed by the spaced studs and the woven wire facings with dampened soil, later removing the temporary strips, and then applying a coating over the opposed faces of the strips and the woven wire and the filling.

In testimony whereof we affix our signatures.

SHERWIN GIBBONS.
HERMAN B. HENSEL.
